CLAIM

The ornamental design for a nurser bottle overwrap, as
shown and described.

DESCRIPTION

FIG. 1 is a perspective view of a nurser bottle overwrap
showing our new design, the broken line disclosure of a
bottle being for illustrative purposes only;
FIG. 2 is a top plan view thereof;
FIG. 3 is a front elevational view thereof;
FIG. 4 is a right elevational view thereof;
FIG. 5 is a rear elevational view thereof;
FIG. 6 is a left elevational view thereof;
FIG. 7 is a bottom plan view thereof.

FIG. 1.

FIG. 2.

FIG. 3.

FIG. 4.

FIG. 5.

FIG. 6.

FIG. 7.
